UNITED STATES PATENT OFFICE.

PERCY TOWNLEY, OF SAN ANTONIO, TEXAS.

CLOTHES PIN OR CLAMP.

1,322,655.

Specification of Letters Patent. Patented Nov. 25, 1919.

Application filed January 3, 1919. Serial No. 269,408.

To all whom it may concern:

Be it known that I, PERCY TOWNLEY, a citizen of the United States, and a resident of San Antonio, in the county of Bexar and 5 State of Texas, have made certain new and useful Improvements in Clothes Pins or Clamps, of which the following is a specification.

My present invention relates generally to 10 clothes pins and more particularly to a metal clamp to not only take the place of the ordinary wooden clothes pin, but to go materially beyond the same in use in so far as clasping qualities and durability, as well 15 as convenience are concerned, my object being the provision of a simple, inexpensive and practically indestructible clamp, the details of which I will now proceed to describe with reference to the accompanying drawing forming a part of this specification, and 20 wherein:

Figure 1 is a side view showing the clamp in position preparatory to use;

Fig. 2 is a similar view illustrating the 25 clamp in operative position;

Fig. 3 is a perspective view of the clamp, and,

Fig. 4 is a front elevation thereof.

Referring now to these figures, my invention 30 proposes a clothes pin or clamp formed of a single volute section of a double strand of spring wire, the strands of which are indicated respectively at 10 and 11 and the free ends of the section of wire being permanently joined as by means of solder, 35 welding and the like, as at 12. The bending of this section of double strand wire, preferably rust-proof wire, forms an oval shaped body 13, the end portions 14 and 15 of 40 which overlap one another and are each

given a reverse curve as at 16, adjacent the extremity thereof. In this way each extremity of the volute section of wire curves outwardly beyond the limits of the body 13, so that either extremity may be readily 45 slipped over a clothes line such as indicated at A in Figs. 1 and 2, and over a fabric B on the clothes line to clasp the clothes line and fabric between the end portions 14 and 15, as clearly indicated in Fig. 2, for which 50 purpose the strands of the end portion 14 are spread or spaced apart to receive the end portion 15 therethrough.

By virtue of its durability, it is obvious 55 that a clothes clamp of the nature of the present one may be left on the clothes line so as to be ready for convenient use at all times, and that in its use all danger of breakage with thick heavy goods such as blankets and the like is avoided. 60

By using a rust-proof wire all danger of 65 marring or staining the clothes is likewise avoided, and its durability renders it greatly superior to the ordinary wooden clothes pin now used for the same purpose.

I claim:—

A clothes pin or clamp of the character described, consisting of a single loop of spring wire embodying two strands, the ends of which terminate in approximately 70 parallel lapping relation at one side of the loop and the strands of one end of which are spaced apart to receive between them the outwardly projecting opposite end of the loop whereby to form a clasp approximately 75 within the limits of the loop between one side thereof and the said outwardly projecting end of the opposite side, as described.

PERCY TOWNLEY.
